UNITED STATES PATENT OFFICE.

JOHN J. GOULD, OF WOODSTOCK, ILLINOIS.

CLOTHES-LINE HANGER.

1,073,230.

Specification of Letters Patent. Patented Sept. 16, 1913.

Application filed January 31, 1913. Serial No. 745,472.

To all whom it may concern:

Be it known that I, JOHN J. GOULD, a citizen of the United States, residing at Woodstock, in the county of McHenry, State 5 of Illinois, have invented certain new and useful Improvements in Clothes-Line Hangers; and I do hereby declare the following to be a full, clear, and exact description of the invention, such as will enable others 10 skilled in the art to which it appertains to make and use the same.

This invention relates to combination clothes lines and has for an object to provide a clothes line upon which the clothes may 15 be secured within the house, the line then being adapted to be folded to facilitate carrying the clothes out of doors in a clothes basket, the line being then adapted to be extended and supported from posts 20 out of doors, thus obviating the necessity of the discomforting operation of securing clothes to a line out of doors in winter weather.

A further object is to provide novel 25 hangers for supporting the clothes line indoors, one of the hangers having a detachable portion equipped with a hook for attachment to an out of doors supporting line.

With the above objects in view the invention 30 consists of certain novel details of construction and combination of parts herein-after fully described and claimed, it being understood that various modifications may be made in the minor details of construction 35 within the scope of the appended claims.

In the accompanying drawings illustrating 40 this invention:—Figure 1 is a front elevation showing the line in-doors. Fig. 2 is a front elevation showing the line in-doors and collapsed to facilitate the attached 45 clothes being dropped in a bundle in the clothes basket. Fig. 3 is a front elevation of the clothes line out of doors. Fig. 4 is a detail perspective view of one of the hangers. Fig. 5 is a detail perspective view of 50 the other hanger. Fig. 6 is a detail perspective view showing the manner of attaching each snap hook to the clothes line. Fig. 7 is a fragmentary sectional view on line 7—7 55 Fig. 5. Fig. 8 is a fragmentary sectional view on line 8—8 Fig. 6.

Referring now to the drawings in which like characters of reference designate similar parts, 10 designates a limp clothes line 55 which is provided at equally spaced intervals with snap hooks 11 of ordinary char-

acter, metal bands 12 being wrapped about the eyes of the hooks and the line to fixedly secure the hooks to the line.

For supporting the clothes line in-doors 60 I provide a pair of hangers designated in general by the numerals 13 and 14 respectively. The hanger 13 comprises a wall plate 15 which is adapted to be secured to the wall 16 of a room and is provided with 65 hinge ears 17. A straight bar 18 is provided at the upper end with an eye 19 through which and the hinge ears a pivot pin 20 is passed. The bar is provided on one side with spaced guide eyes 21 and 22. 70 A stiff wire rod 23 is slidably engaged in the guide eyes and is adjustably secured in the upper guide eye 21 by means of a set screw 24. The rod is bent into a loop 25 below the bar 18, one end of the wire being 75 directed rearwardly from the loop and forming a buffer arm 26 which is terminally equipped with a rubber cap 27 that engages the wall of a room and prevents mutilation of the wall paper. A helical spring 28 is 80 connected to the rod and is equipped with an eye screw 29 which is adapted to be fixed in the wall to normally hold the cap in engagement with the wall, this spring yieldably resisting swinging of the loop out from 85 the wall.

The hanger 14 comprises a ceiling plate 90 30 which is adapted to be secured to the ceiling by screws 31 or otherwise. An outer tube 32 is carried by the ceiling plate and into this tube is telescoped an inner tube 33 which is adjustably secured in position by means of a set screw 34 threaded through the outer tube and terminally selectively engaged in any one of a series of notches 35 95 formed in the inner tube. A stiff wire rod 36 is adjustably secured in the lower end of the inner tube by means of a set screw 37, this rod being terminally bent to form a loop 38 one end of which is bent rearwardly 100 to form a buffer arm 39 that is terminally equipped with a rubber cap 40 to engage the wall of the room. The rod 36 is provided near the loop with a downwardly opening hook 41 the purpose of which will 105 presently be explained.

In operation, all of the snap hooks are 110 engaged with the loop 25 of the hanger 13 and the clothes line 10 hangs limp in a series of folds. To apply the clothes the snap hook at one end of the line is disengaged from the loop 25 and then engaged with the

loop 38 of the hanger 14 as shown in Fig. 1 with a resultant taut portion of the line being exposed between the loops of both hangers to receive the clothes which are applied with ordinary clothes pins. By removing the snap hooks in succession from the loop of the hanger 13 and transferring them to the loop of the hanger 14, and securing the clothes to the resultant straight portion of the clothes line, all the snap hooks will finally be engaged with the loop of the hanger 14 and the applied clothes will drop with the folds of the clothes line as clearly shown in Fig. 2. By unloosening the set screw 37 the loop of the hanger 14 may be bodily removed and dropped with the bundle of clothes into a clothes basket 42.

The clothes basket may now be carried out of doors and the hook 41 of the detached loop 38 applied to an ordinary clothes line 43 which is supported terminally by posts 44. The terminal snap hook remote from the loop may now be engaged with a staple 45 in one of the posts and the snap hooks in succession engaged with the clothes line as clearly shown in Fig. 3 until all of the clothes have been removed from the basket whereupon the loop 38 may be manually slid longitudinally of the clothes line 43

until the limp clothes line 10 is taut from end to end, such operation effecting the hanging of the clothes out of doors in a minimum time and with minimum exertion and thus avoiding the usual discomforts due to this operation.

What is claimed, is:—

1. A hanger of the class described comprising a plurality of telescopic sections, means to secure said sections in adjusted relation, a loop on one of said sections, and a buffer extending laterally from said loop.

2. A hanger of the class described including a bar having an out-turned ear at its lower end, a guide on said bar in alignment with said ear, a rod passing through said guide and ear and bent below the ear to form a loop, the end of said rod below the ear being bent to extend laterally of the loop and constituting a buffer arm, hinge means to support said hanger, and other means to secure the rod in adjusted position relative to the bar.

In testimony whereof, I affix my signature, in the presence of two witnesses.

JOHN J. GOULD.
